UNITED STATES PATENT OFFICE.

HASWELL A. SWASEY, OF NEW ORLEANS, LOUISIANA.

MOP.

Application filed September 9, 1922. Serial No. 587,142.

To all whom it may concern:

Be it known that I, HASWELL A. SWASEY, a citizen of the United States, residing at New Orleans, in the parish of Orleans and 5 State of Louisiana, have invented a new and useful Mop, of which the following is a specification.

This invention relates to brushing and scrubbing, and more particularly to floor 10 mops of the type known as dry hand mops.

The object of the invention is to provide a mop of this character so constructed that it may be wrung dry without wetting the hands, which is self wringing and self 15 rinsing and which may be used as a scrub mop in addition to performing the functions of the ordinary mop.

Another object is to provide a mop, the head or mopping element of which may be 20 readily renewed by an inexperienced person, and which is constructed to preclude its losing its shape or symmetry, and which when in operation presents a solid mopping surface thereby adapting it for use in 25 scrubbing as well as mopping.

Another object is to provide a mop of this character in which the head is so mounted on the frame as to prevent all 30 possibility of scratching the floor or furniture.

Another object is to provide a mop of this character composed of few parts and including a frame having a cylindrical hand 35 grip molded integral therewith and which is strong and free of any attachments such as would be likely to get out of order.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 45 within the scope of what is claimed without departing from the spirit of the invention.

In the accompanying drawings:

Figure 1 represents a side elevation of a 50 mop constructed in accordance with this invention with parts of the handle broken out for convenience in illustration, and the mopping member stretched prior to wringing;

Figure 2 is a bottom plan view;

Fig. 3 is a transverse section taken on the 55 line 3—3 of Fig. 1;

Fig. 4 is a section on line 4—4 of Fig. 1;

Fig. 5 is a side elevation of the connector;

Fig. 6 is a detail section of the mop;

Fig. 7 is a side elevation of the mop in 60 position ready for use as a scrubber;

Fig. 8 is a similar view with the mop thrums shown twisted for wringing; and

Fig. 9 is a section taken on line 9—9 of 65 Fig. 7.

In the embodiment illustrated, the mop constituting this invention comprises a mop head holder or frame 1 slidably mounted on a handle 10 and connected therewith by a mopping element or head 20, the head 70 being secured to the handle by a connector in the form of a clamp 15.

The frame 1 which constitutes a part of the invention is constructed of rust proof metal in elongated bail-shaped form with 75 the side members 2 and 3 diverging toward their outer ends, and connected by a cross bar 4. This cross bar 4 has a plurality of longitudinally spaced apertures 5 for the connection of the head 20 therewith in a 80 manner presently to be described.

The inner ends of the side bars 2 and 3 of frame 1 are connected by a cross bar 6 which is widened as shown clearly in Fig. 3 to form a hand guard to prevent the contact of the user's hand with the mop head 20, and against water during the wringing operation of the mop. Extending centrally outward from the cross bar 6 is a handle encircling cylindrical hand grip 7, the outer 90 face of which is knurled or serrated as shown at 8 to afford a firm grip during the wringing operation. This cylindrical hand grip 7 is provided at its outer end with a bead 9 which prevents the hand of the user 95 from slipping off the member 7.

The handle 10 may be of any desired length and preferably constructed of hard wood, with a portion thereof peripherally corrugated to provide a hand grip 11 which 100 is positioned at any suitable point convenient for the user.

The connector 15 which is designed for securing the head or mopping element to the lower end of the handle 10 may be of 105 any suitable or desired construction, but is preferably made in the form of two semi-circular jaws 16 and 17 of rust proof metal,

UNITED STATES PATENT OFFICE.

JOSEPH B. TAYLOR, OF ALLENDALE, NEW JERSEY.

DUST SEPARATOR.

Application filed November 3, 1921. Serial No. 512,527.

To all whom it may concern:

Be it known that I, JOSEPH B. TAYLOR, a citizen of the United States, residing in Allendale, county of Bergen, State of New Jersey, have invented certain new and useful Improvements in Dust Separators, of which the following is a specification.

The present invention has relation to a compact, novel and efficient apparatus for separating solid particles held in suspension in a fluid; and more particularly to an improved means for separating dust, smoke and fumes from air and other gases.

My improved apparatus operates, broadly speaking, upon the principle of projecting gases at a high velocity against collecting surfaces so as to cause the suspended dust to stick to the surface, building up to form ridges or buttons. This principle is preferably embodied in apparatus so constructed as to utilize centrifugal force as well as the sticking due to impact. Concave perforated receiving surfaces are preferably employed, which are backed up by dead air chambers, and it is preferred, also, to cause the air to be diverted from one surface to another (whether perforated or not).

The apparatus is simple and inexpensive, takes up little room and may be made very light. It is preferably formed of separable and similar units which can be so used as to build up a complete separating apparatus whose component parts are capable of mutual adjustment with regard to the particular conditions to be met in each case.

For the sake of brevity, the following specification will be limited to the description of means for separating dust, smoke or fumes from air or other gases; but the invention is not limited to apparatus for this purpose, since it may also be used for separating solids in suspension in liquids. Accordingly the expression "dead air space" and the like is to be understood as a convenient expression covering a space containing any fluid (liquid or gas) in a quiescent condition.

A preferred embodiment of the invention is illustrated in the accompanying drawings, wherein Figure 1 is a top plan view of the entire apparatus, Figure 2 is a side elevation of the same showing a part of one wall broken away, Figure 3 is a plan view of one end showing the top or cover

removed, Figure 4 is a sectional view taken on the line 4—4 in Figure 3, and Figure 5 is a partial diagrammatic view of a modification.

The dust separator proper is enclosed within an outer casing 10 set over a dust hopper 11, through which the dust is finally carried off, and suitable doors, 12 and 13, operated by handles 14 or the like, serve as a floor for the primary dust-receiving chamber. By opening these doors momentarily from time to time, the dust collected above them is allowed to drop into the hopper.

The separator proper is divided into two parts by a perforated floor 15 which supports the separating units in the separating chamber above the floor. These units extend from this floor all the way to the top of the main casing, which is also the top of the separating chamber. The space between the floor 15 and the doors 12, 13, is the primary dust-receiving chamber.

Each separating unit is preferably composed of a transversely placed row of boxes, separated by narrow vertical air passages preferably made wedge-shaped with the outlet at the narrower end of each, as shown at 16. In the form shown the successive groups of boxes contain respectively three and two complete boxes alternately. The groups having only two complete boxes have half boxes at each end to fill up the width of the separating chamber. Any desired number of transversely arranged groups may thus be employed, the separating chamber being correspondingly long. These groups, being independent can be adjusted in regard to their relative position to suit conditions.

Each separating box comprises two dead-air chambers 17 and 18 (see Figure 3) separated by an internal imperforate partition 19. The rear of each chamber 17 and the front of each chamber 18 is enclosed by a cylindrical wall 20, 21, respectively. These walls are concave outward and are perforated, preferably being made of thin metal with short horizontal slits as shown at the left in Figure 4.

The arrangement thus described is such that the front end of each air passage 16 is directly opposite the middle of a perforated wall 20.

The dust-laden air, coming in at the rear

end of the apparatus through a pyramidal distributing passage 22, first enters a vestibule 23 over one end of the perforated floor 15, and strikes a cross partition 24. 6 Wedge-shaped air passages 25 extended forward within this partition and direct the air currents against the walls 20 of the first separating boxes. The coarser particles of dust will be largely arrested within the 10 vestibule 23, dropping through the openings in the floor 15 into the primary dust-receiving chamber. The remainder of the dust will pass through the passages 25 and will strike the concave walls 20. Part of this 15 dust will stick to the solid parts of the wall 20, a part will pass directly through the perforations and will stick to the inner partitions 19, and a part will be separated by centrifugal force from the sharply di- 20 verted air stream, passing through the perforations in the walls 20, and falling to the bottom and through the floor 15. The air, after striking each wall 20 will be sharply diverted by the concavity of 25 each wall, so as to flow back against the front face of the partition 24. Here a part of the dust will stick, while the remainder will flow forward with the air through the first set of passages 16. 30 As the air emerges from these passages it will lose a further proportion of the suspended dust by a repetition of the process just described, in each case being sharply diverted backward against a collecting element. Instead of a partition as 35 24, being the collecting elements, however, I prefer to employ dead air chambers 18, as already described; so that the dust will be collected partly by sticking and partly 40 by centrifugal force in the forwardly facing elements, as already described with respect to the rearwardly facing elements. In its broadest aspect, however, the invention comprises the use of collecting elements which 45 divert and reverse the air currents in the manner described, whatever the nature of these elements. It is quite within the scope 50 of the invention to make all the collecting walls imperforate. The dust which sticks to the various surfaces of the apparatus described can be 55 easily dislodged from time to time by percussion, and will fall through the perforations in the floor 15. In order to prevent the air from passing down through the perforations between two sets of separating elements and upward through the floor to 60 elements further on, partitions 26 are used, which divide the primary dust-receiving 65 chamber into a succession of dead air chambers. These partitions extend across the device immediately under the partition 24 and the successive partitions 19. 70 When the air has passed all the separating 65 elements, it emerges, preferably through the

tapering outlet 27. As it leaves this outlet it will be found to contain only a very small percentage of suspended matter.

Many changes may be made in this apparatus without departing from the scope 70 of the invention, and I do not limit myself to the details herein shown and described.

What I claim is:—

1. The process of separating dry dust from a gas in which it is held in suspension 75 which consists in causing said dust to collect in a pile upon a dry collecting surface by driving the dust laden gas in a rapid concentrated stream against such collecting plate in a direction substantially normal to 80 said plate.

2. Separating apparatus of the character described comprising a pair of concave forward facing collecting elements, a concave backward facing collecting element displaced laterally with respect to said first named elements, and means for projecting fluid between said first named elements, against substantially the middle of said 90 backward facing element.

3. Apparatus as in claim 2 wherein the backward facing element is a dead air chamber having a perforated outwardly concave enclosing wall.

4. Apparatus as in claim 2 wherein both 95 the backward facing and the forward facing element is composed of a dead air chamber having a perforated outwardly concave enclosing wall.

5. Apparatus as in claim 2 wherein both 100 the backward facing and forward facing element is composed of a dead air chamber having a perforated cylindrical outwardly concave enclosing wall, and wherein the two cylinders are laterally displaced with respect 105 to each other.

6. Apparatus as in claim 2, wherein each collecting element is composed of a number of concave walls separated by air passages, each air passage being adapted to direct a 110 fluid stream against the concave wall of the element in front of it.

7. Apparatus as in claim 2 combined with a succession of dead air chambers constituting a primary dust collecting chamber and 115 separated from the collecting elements by a perforated floor.

8. In a dust separator, a separating box having an outwardly concave perforate enclosing wall and means for projecting a current of air against the outside of said concave wall in a direction substantially normal thereto.

9. In a dust separator, a separating box having two oppositely placed outwardly 120 concave walls and an intermediate imperforate partition adapted to divide the box into two independent sections.

10. In a dust separator, a group of outwardly concave dead air boxes having out- 125

wardly concave perforated walls placed side by side and separated by air passages; in combination with a second similar group of boxes and air passages so placed that the 5 passages of one group terminate opposite the concave wall of the next group.

11. Apparatus as in claim 10 wherein the successive groups of boxes are made adjustable with relation to each other

10 12. The process for separating dry dust from gases which consists in projecting the gas to be treated in a localized stream against a receiving surface at such a velocity as to cause the dry dust to adhere and build 15 up in a pile opposite the point of projection.

13. A dust separator comprising oppositely facing rows of dust collecting walls placed side by side, all of the walls of one row being concave toward those in the other, 20 the walls of one row being laterally displaced with respect to those in the other, and the walls in one row at least being perforated, dead air chambers behind the perforated walls, and passages between the walls 25 in one row adapted to direct air currents against substantially the middle of the walls in the other row.

In testimony whereof I have hereto set my hand on this 2nd day of November, 30 1921.

J. B. TAYLOR.
